ATTORNEYS

UNITED STATES PATENT OFFICE.

EDWARD L. HESSEL, OF MINNEAPOLIS, MINNESOTA, ASSIGNOR TO AMERICAN PLUMBING & HEATING COMPANY, OF MINNEAPOLIS, MINNESOTA, A CORPORATION OF MINNESOTA.

RADIATOR STAND.

Application filed February 15, 1926. Serial No. 88,326.

This invention relates to a stand structure, as a support for a radiator, when, during a building operation, and before inside finishing is completed, the radiator is temporarily set up and connected, for drying purposes.

The invention is most often used for temporarily supporting footless radiators, adapted in permanent use to be disposed upon or suspended from wall brackets free of the floor. The device provides means whereby a radiator of the above mentioned type can be conveniently temporarily supported at any desired location, in upright position, for connection with the steam line.

Objects are to provide a plural part knock-down stand, having pedestal elements adjustable toward and away from one another to fit any radiator, and adapted to wedgingly and clampingly engage between the radiator sections, or units, and further adapted to be clamped in adjusted position to form a rigid temporary support.

Features of the invention include the structure of the pedestal elements or stand members as castings, two in number, each having a floor engaging foot, an elongated radiator engaging portion shaped to wedgingly fit between adjacent radiator units, and each further having a cored opening therethrough, adjacent the foot, parallel with direction of adjustment of the elements and substantially at a right angle to the radiator-engaging portion.

The advantages of the device will appear in the description of the drawings forming part of this specification, and in said drawings.

Figure 1 is an end view radiator supported by the improved stand, one of the pedestal elements and a portion of the tubular connecting member being shown in section;

Figure 2 is a plan section on line 2—2 of Figure 1;

Figure 3 is an outer side view of one of the pedestal members.

The device comprises three parts, two identically constructed interchangeable, pedestal elements, and a cross connector member upon which the elements are adjustable.

Each pedestal element or stand member 1 in the form of a casting, provides an elongated radiator-engaging portion 2, cross sectionally configurated to wedgingly engage

between and against adjacent radiator units 10, longitudinally thereof. In this instance 55 this engaging portion has angularly related wings 3 providing inclined wedge surfaces, engageable with the outer portions of the units as shown in Figure 2. Each member has a foot 4 extending outwardly at right 60 angles to the inner surface of the pedestal, and adjacent and above the foot the pedestal has a cored opening 6 provided in an annular extension 7, disposed laterally at the outer side of the member, at right angles to the 65 vertical radiator engaging portion. The axis of the extension 7 is in this instance disposed substantially one-quarter of the length of the pedestal above the foot, which gives the proper stability when the pedestals are 70 set up with the cross member 9 slidably traversing the opening. Strengthening ribs 5 give rigidity with a minimum of weight. A set screw 8 provides means for holding the pedestal in adjusted position upon the 75 cross or connector member.

The cross members may be cut on the job from a length of pipe of proper diameter. Moreover, the pedestal members can be conveniently stored.

The device can be connected with the radiator while the same is lying upon its side, by slightly raising the radiator at one end, positioning of the pedestal elements between adjacent radiator units at each end, then 85 properly positioning the companion elements, running respective connector members through the openings of each pair of opposingly related elements, and then tightening the set screws, whereafter the radiator 90 and attached pedestals, can be simply raised to upright position.

I claim as my invention:

1. A device of the class described, comprising two pedestal elements, having elongated portions for wedgingly engaging at opposite sides of and between adjacent radiator units, a cross member slidably in and adjustably connecting said elements, and set screws for engaging said cross member, said member positioned at a level to pass beneath radiator units.

2. A device of the class described, a pair of elongated longitudinally reinforced radiator-supporting stand members, each having 105 a foot, and each having a wedge-like radiator

engaging portion above the foot, and a cross brace receiving opening intermediate the foot and wedge-like engaging portion, extending at a right angle to said portion, and each having a set screw adapted to enter said opening, and a cross brace traversing said openings for permitting adjustment of the

members towards and away from one another, and said openings arranged below the level of the bottom of the units of the 10 radiator supported by the device.

In witness whereof, I have hereunto set my hand this 9th day of February 1926.

EDWARD L. HESSEL.
